(57) **CLAIM**

(21) Appl. No.: **29/154,521**

The ornamental design for a postcard box containing a spray dispenser, as shown and described.

(22) Filed: **Jan. 28, 2002**

DESCRIPTION

(30) **Foreign Application Priority Data**

Oct. 11, 2001 (XH) DM/057629

FIG. 1 is a perspective front view of the postcard box with the head of the spray dispenser sealed by a removable tab shown in dotted line;

(51) **LOC (7) Cl.** **19-01**

FIG. 2 is a perspective rear view of the postcard box of FIG. 1;

(52) **U.S. Cl.** **D19/2; D9/300**

FIG. 3 is a front plan view of the postcard box of FIG. 1;

(58) **Field of Search** D9/300, 416; D28/91.1;

FIG. 4 is a rear plan view of the postcard box of FIG. 1;

383/103; 215/383, 900; 426/124, 85; 222/402.1;

FIG. 5 is a front plan view of the postcard box of FIG. 1 with the sealing tab removed, showing the head of the spray dispenser;

220/23.8; 206/162, 820, 232; D19/1-3;

FIG. 6 is a rear plan view of the postcard box of FIG. 5;

40/124.1

FIG. 7 is a top view of the postcard box of FIG. 1 as shown in FIG. 5; and,

FIG. 8 is a bottom view of the postcard box of FIG. 1.

FIG. 8 is a bottom view of the postcard box of FIG. 1.
